UNITED STATES PATENT OFFICE

2,513,119

MOBILE TRIMMING APPARATUS

Harold E. Stout, West Leesport, Pa., assignor to Textile Trimming & Boarding Machine Company, Reading, Pa., a corporation of Pennsylvania

Application March 8, 1949, Serial No. 80,123

16 Claims. (Cl. 26—11)

1

This invention generally relates to thread clipping machines or the like, such as the one disclosed in F. Y. Kitzmiller U. S. Patent No. 2,113,112, which was issued April 5, 1938; and more particularly concerns a unique mobile unit of this type, which can be readily moved from place to place in a work room or shop, as needed, to carry out certain labor saving functions in an expeditious and advantageous manner.

The machine or apparatus disclosed in said patent, is adapted to carry out its labor saving functions in connection with the manufacture of sewed, woven, or knitted fabrics and materials, articles of wearing apparel and clothing, and other articles such as bed sheets, pillow cases, watch bands, etc. The various parts of this apparatus are arranged to form a permanent installation which comprises a stationarily mounted power unit adapted to provide the operating power and generate a suction for, one or more separate hand controlled and manipulated cutting or clipping devices used by individual operators at different work tables that are spacedly arranged in a room at different distances from the power unit. It has been found in practice, that such an installation is highly efficient and effective as a labor saving means, in conjunction with large volume operations, involving conditions where each operator at a separate work table is in more or less constant need of the clipping device that serves his particular table. In other words, such an installation is particularly advantageous in connection with the manufacture of the above indicated fabrics, materials and articles, on a large or unlimited scale. However, where the manufacturing facilities are more or less limited, the initial cost and large scale operating capacity of such equipment are usually too great to make its acquisition and use profitable. Nevertheless, small manufacturers are just as much concerned with the problem of reducing their labor costs as the larger manufacturers, and as a consequence, a demand has been created for a relatively cheaper apparatus of the above mentioned type, which more particularly serves the needs of the smaller manufacturers of the indicated fabrics, materials and articles, and can be profitably used to advantage in cases involving cutting, clipping, or trimming operations on a smaller scale than that served by the equipment now available for this purpose and at the same will allow the use of the apparatus in conjunction with any operation that is performed before or after the cutting, clipping or trimming operation as for example in a continuous production line in which it is found necessary to add an additional clipping or trimming operation without interrupting the routine or consecutive flow of the material or make necessary an extra handling of it.

2

One object of my invention is to provide a novel mobile apparatus, or unit, of the type indicated, which solves the mentioned problem and successfully meets the referred to demand.

5 Another object is to provide such a mobile unit which can be readily moved from place to place in a work room, or shop, as desired, to carry out cutting, clipping, trimming and cutting waste disposal operations, at its point of location, to the same extent as effected at a particular location by the more expensive and involved equipment heretofore available for this purpose.

10 A further object is to provide such a mobile unit having certain structural and functional features of advantage over the similar equipment of the prior art.

15 An additional object is to provide such a mobile unit which is simple in construction and operation, and which is particularly designed to affect investment, maintenance and operating economy, particularly where only limited use for such equipment is involved.

20 It is also an object to provide such a mobile unit which can be temporarily used to advantage at one location after another in a work room or shop to carry out certain labor saving operations as required at different times at said locations.

25 Other objects are, to provide a mobile unit of the type indicated which comprises a movable support in the form of a table having a flat top on which the work may be carried out, and a bracket positioned above the table top for conveniently holding a clipping, cutting, or trimming device in out-of-the-way location while not in use; which table is also provided with such features as suitable enclosed shelf means for supporting a suction generating device, a cutting waste receiving device and drive means for the clipping device; and which table is so arranged as to provide ample knee room for the operator sitting adjacent thereto, and has associated therewith means for maintaining the table in stationary position after it has been moved to its location of use.

30 35 40 45 50 55 With these and other objects in view, which will become more apparent from the following detailed description of one practical and illustrative embodiment of my improvements as shown in the accompanying drawings, the invention comprises the novel unit, elements, features of construction and arrangement of parts in co-operative relationship, as more particularly defined by the hereto appended claims.

In the accompanying drawings:

Figure 1 is a front elevational view of one form of the novel mobile apparatus, or unit, which embodies my invention.

60 Fig. 2 is a plan sectional view of the unit

shown in Fig. 1, taken substantially as indicated by the arrows 2—2 on Fig. 1.

Fig. 3 is an end elevational view of the unit shown in Fig. 1, as seen by looking at the latter from the right, and

Fig. 4 is an enlarged, partial, vertical, sectional view through the cutting waste receiving device of the unit, taken substantially as indicated by the arrows 4—4 on Fig. 3.

The mobile apparatus or unit disclosed in the present application, is designed for use in garment factories, hosiery mills and other places where the above indicated fabrics, materials and articles are produced on a more or less extensive scale, to either supplement stationary equipment or installations of the type disclosed in said Patent No. 2,113,112, or to function as a substitute therefor, in places where it can be utilized to advantage by itself. As the description proceeds, it will be realized that the present invention consequently supplies a need and produces certain advantageous results not attainable with equipment heretofore available for this purpose.

The form of my invention shown in the drawings generally comprises a readily movable support or table 1, having associated therewith, or mounted thereon, a power operated cutting, trimming, or clipping device 2, a cutting waste receiving device 3, a suction generating device 4, an electric motor 5, an electric switch device 6, and an electric junction box 7.

The structural parts of the movable support or table 1, such as the flat table top 8, and legs 9, are preferably, but not necessarily, made of metal. The bottom ends of the legs 9 are provided with suitable standard rolling means, such as wheels, castors, or the ball roller devices 10 indicated in the drawings, that are arranged to facilitate rolling action, or movement of the table along the floor, from place to place. A platform, or shelf 11, is horizontally secured to the table legs 9 and arranged to have mounted thereon the cutting waste receiving device 3, suction generating device 4, motor 5 and junction box 7.

The parts between the table top 8 and the shelf 11 are protected by an arrangement of vertically positioned sectional panels 13, made of metal, wood, or other material, which are detachably applied around the entire table, by suitable means, such as screws 13a. At the front, the table is recessed, as indicated by the numeral 14 in Fig. 2, to provide ample knee room for the operator that sits adjacent the table at the location of said recess.

Fixedly secured to the table top 8, is a vertical standard or post 15. The latter has fastened thereto a horizontally extending bracket arm 16, by means of a finger operated set screw 17, so as to permit convenient selective vertical positional adjustment of the arm 16 on the post 15. The arm 16 is provided at its outer end with a spring clamp 18, arranged to removably hold in position a standard type of hand-manipulated and power operated thread clipping device 2, such as the one disclosed in my said Patent No. 2,113,112, or some other similar cutting device. The thread clipping device 2 comprises usual power operated cutting or clipping means indicated by the numeral 19, and a suction nozzle 20 which is located directly adjacent thereto. A flexible conduit 21 has one end thereof connected to the rear of the device 2 and the other end thereof connected to a top inlet extension 22 of the cutting waste receiving device 3. The clipping means 19 is operated by a flexible rotatable cable 23, one

end of which is connected to the rear of the device 2 and the other end of which is connected to the motor 5.

The device 2 is utilized in usual and well known manner by withdrawing it from the clamp 18 and manually bringing it to a convenient holding or operating position where the clipping means 19 will function to cut off the surplus material, loops, threads, etc., from a certain fabric, material, or article, lying on the table top 8, or held in hand by the operator. In this connection the air suction of the adjacent nozzle 20 of the device 2, first exerts a lifting action on the material to be cut off so as to facilitate the cutting action by the clipping means 19. The cutting waste severed by the clipping means will then be picked up by the suctional air flow entering the nozzle 20, will be suctionally pulled through the hollow handle section of the device 2, and then transmitted through the flexible conduit 21 to the waste receiving device 3, in a manner which will become apparent as the description proceeds. The operator sitting at the table, utilizes the clipping device 2 for various purposes in connection with his work on fabrics, materials and articles of the type previously mentioned, and for more detailed information concerning the construction, operation and utilization of the device 2, reference may be had to said Patent No. 2,113,112.

The suction generating device 4 comprises a standard form of suction developing turbine wheel (not shown) that is rotatably mounted in a housing or casing 24, an electric motor 25, and a belt drive connection 26 arranged to operatively connect the said motor and turbine wheel for rotation in unison. An air outlet pipe 27 is arranged to extend from the turbine housing 24, and is covered with a coarse mesh cloth or fine burlap 27a, so as to effect muffling of the outrushing air.

The cutting waste receiving device 3 may follow a more or less standard construction of the type comprising a cylindrical casing 28, adapted to have removably mounted therein a waste receiving receptacle 29. In the present instance, the forward end of the receptacle 29 is provided with a flange 30 whose outer edge has secured thereto a circumferential rubber ring 31, adapted to be seated against an annular internal partition 32 of the casing 28. The receptacle 29 is provided with similar arcuate handles 33 at the opposite ends thereof, and comprises a frame 34 of flat rigid strip metal or other material, which is covered by a fine wire mesh, or coarse cloth material 35, circumferentially and across its bottom section, as clearly shown in Fig. 4. A bracket member 36 is fixedly secured to the casing 28 and arranged to serve as a support for the rear end of the receptacle 29, when the latter is in its cutting waste receiving position shown in Fig. 4. The front end of the casing 28 is provided with a removable flanged lid 28a, which is detached when it is desired to remove, or pull out the receptacle 29 for emptying or other purposes.

The suction generating device 4 is connected with the rear end of the casing 28 by a flexible conduit 37 and when the device 4 is in operation, a suctional air flow is created by the latter through the various connected parts, which begins at the nozzle 20 of the device 2 and causes the cut off waste material severed by the clipping means 19 to enter the nozzle 20, pass through the hollow handle section of the device 2, then through the flexible conduit 21, through casing extension 22, into the receptacle 29, as indicated

by the arrows in Fig. 4, where it is collected for disposition as desired. The suctional air flow continues through the wire mesh 35 of the receptacle 29 to the suction generator 4 and escapes through the outlet pipe 27.

The electric motors 5 and 25 are connected in usual and well known manner with the switch 6 and terminal box 7, by conductors 38, 39, and 40, and an electric cord 41 which is provided with a connecting plug 42, is arranged to extend from the terminal box 7, for convenient connection of the electrical system with the socket of a power line. A switch handle 6^a, extending from the switch box 6 provides control for the electrical system, and when the handle 6^a is moved to its "on" position, the motors 5 and 25 are operated by the electrical current so that the flexible cable 23 rotatively drives the clipping means 19 of the device 2, and the motor 25 drives the suction developing turbine wheel within the housing 24.

After the table 1 has been moved to its desired work performing location, it may be maintained in fixed or stationary position by suitable table movement preventing means, such as the separate flat metallic plates 43 shown in Fig. 1, that are provided with central apertures 44, into which snugly fit the ball rollers 10, so that they are held in spaced relation from the floor surface. The plates 43 can be quickly and easily slipped into position beneath the table legs 9, and removed therefrom, whenever it is desired to move the table to a different location.

Of course, the mobile machine or apparatus shown and described, can be changed and modified in various ways, without departing from the invention herein disclosed and more particularly defined by the hereto appended claims.

I claim:

1. A textile apparatus of the character described comprising; a movable support; a device provided with power operable cutting means and a suction nozzle adjacent to the latter; holding means on the support for determinately positioning said cutting device and suction nozzle; means arranged to effect operation of the cutting means; a cutting waste receiving device; suction generating means; conduit means connecting said suction nozzle, waste receiving device and suction generating means; said movable support combining all of said means and device into mobile cooperative relationship.

2. A textile apparatus of the character described comprising; a device provided with power operable cutting means and a suction nozzle adjacent to the latter; holding means for determinately positioning said cutting device and suction nozzles; means arranged to effect operation of the cutting means; a cutting waste receiving device; suction generating means; conduit means connecting said suction nozzle, waste receiving device and suction generating means; a work table supporting said means and devices in cooperative relationship; and means on said table arranged to facilitate movement of the latter along the floor.

3. A textile apparatus of the character described comprising; a device provided with power operable cutting means and a suction nozzle adjacent to the latter; holding means for determinately positioning said cutting device and suction nozzle; means arranged to effect operation of the cutting means; a cutting waste receiving device; suction generating means; conduit means connecting said suction nozzle, waste receiving

device and suction generating means; a work table supporting said means and devices in cooperative relationship; ball rollers mounted at the bottom of said table to facilitate movement of the latter along the floor; and means arranged to effect spaced positioning of said ball rollers from the floor.

4. A textile apparatus of the character described comprising; a device provided with power operable cutting means and a suction nozzle adjacent to the latter; holding means for determinately positioning said cutting device and suction nozzle; means arranged to effect operation of the cutting means; a cutting waste receiving device; suction generating means; conduit means connecting said suction nozzle, waste receiving device and suction generating means; a work table supporting said means and devices in cooperative relationship; ball rollers mounted at the bottom of said table to facilitate movement of the latter along the floor; and a plurality of separate flat plate elements arranged to effect spaced positioning of said ball rollers from the floor.

5. A textile apparatus of the character described comprising; a hand-manipulated device provided with power operable cutting means and a suction nozzle adjacent to the latter; means arranged to effect operation of the cutting means; a cutting waste receiving device; suction generating means; conduit means connecting said suction nozzle, waste receiving device and suction generating means; a work table provided with a flat top section and a shelf therebeneath for supporting the suction generating means, cutting waste receiving device and means arranged to effect operation of the cutting means; and a bracket extending above said table top section arranged to detachably maintain the hand-manipulated device in inactive position.

6. A textile apparatus of the character described comprising; a hand-manipulated device provided with power operable cutting means and a suction nozzle adjacent to the latter; means arranged to effect operation of the cutting means; a cutting waste receiving device; suction generating means; conduit means connecting said suction nozzle, waste receiving device and suction generating means; a work table provided with a flat top section and a shelf therebeneath for supporting the suction generating means, cutting waste receiving device and means arranged to effect operation of the cutting means; roller means at the bottom of said table arranged to facilitate movement of the latter along the floor; and a vertically adjustable bracket secured to said table top section and extending above the latter, arranged to detachably maintain the hand-manipulated device in vertically selected position.

7. A textile apparatus of the character described comprising; a hand-manipulated device provided with power operable cutting means and a suction nozzle adjacent to the latter; means arranged to effect operation of the cutting means; a cutting waste receiving device; suction generating means; conduit means connecting said suction nozzle, waste receiving device and suction generating means; a work table provided with a flat top section and a shelf therebeneath for supporting the suction generating means, cutting waste receiving device and means arranged to effect operation of the cutting means; a plurality of detachably mounted panels arranged in vertical relation about the

table so as to enclose said shelf and the parts supported thereon; and a bracket extending above said table top section arranged to maintain the hand-manipulated device in inactive position.

8. A textile apparatus of the character described comprising; a hand-manipulated device provided with power operable cutting means and a suction nozzle adjacent to the latter; means arranged to effect operation of the cutting means; a cutting waste receiving device; suction generating means; conduit means connecting said suction nozzle, waste receiving device and suction generating means; a work table provided with a flat top section and a shelf therebeneath for supporting the suction generating means, cutting waste receiving device and means arranged to effect operation of the cutting means; a plurality of detachably mounted panels arranged in vertical relation about the table so as to enclose said shelf and the parts thereon; a vertically adjustable bracket secured to said table top section and extending above the latter, arranged to detachably maintain the hand-manipulated device in vertically selected position; ball rollers mounted at the bottom of said table to facilitate movement of the latter along the floor; and a plurality of separate flat plate elements each provided with an aperture, arranged to effect spaced positioning of said ball rollers from the floor.

9. A textile apparatus of the character described comprising; a movable support; a device provided with power operable cutting means and a suction nozzle adjacent to the latter; means on said support to effect operation of the cutting means; holding means for determinately positioning said cutting device and suction nozzle; a cutting waste receiving device on said support; suction generating means on said support; and conduit means connecting said suction nozzle, cutting waste receiving device and suction generating means so that the suctional air flow developed by the latter will effect conveyance of the cutting waste from the suction nozzle to the cutting waste receiving device.

10. A textile apparatus of the character described comprising; a movable support; a device provided with power operable cutting means and a suction nozzle adjacent to the latter; mounting means on the support arranged to maintain the device in an adjustable active or inactive position; means on said support to effect operation of the cutting means; a cutting waste receiving device on said support; suction generating means on said support; and conduit means connecting said suction nozzle, cutting waste receiving device and suction generating means so that the suctional air flow developed by the latter will effect conveyance of the cutting waste from the suction nozzle to the cutting waste receiving device.

11. A textile apparatus of the character described comprising; a table top; means for movably supporting said table top; a hand manipulated device provided with material cutting and waste removing means; means for holding said device in a determined position above said table top; and means for operating said cutting and waste removing means below said table top and movable therewith.

12. A portable textile trimming and waste collecting apparatus having in combination with a hand manipulated universally movable device

provided with material cutting and waste removing means; means for holding said device in a determined position; of driving means for operating said cutting and waste removing means; waste collecting means; and means arranged to support said driving means and said waste collecting means in relatively fixed position with respect to said device.

13. A textile apparatus of the character described comprising; a movable support; a hand manipulated device provided with power operable means and a suction nozzle adjacent to the latter; driving means for said cutting means; waste receiving means on said support comprising a cylindrical casing; a removable cover at one end of said casing; a waste receiving receptacle having an open end spacedly mounted within the walls of said casing; an inlet into said casing arranged angularly in the wall thereof for direction of the waste into the open end of said receptacle intermediate said cover and said receptacle; suction generating means carried by said support and connected to said casing; and conduit means connecting said inlet of said casing with said suction nozzle.

14. A portable textile trimming and waste collecting apparatus having in combination with a device provided with material cutting and waste removing means; driving means for operating said cutting and waste removing means; holding means for determinately positioning said cutting means and waste removing means; waste collecting means; and means arranged to support said driving means and said waste collecting means in relatively fixed position with respect to said device.

15. A textile apparatus of the character described comprising; a table top; means for movably supporting said table top; a device located above said table top and provided with material cutting and waste removing means; holding means for determinately positioning said cutting means and waste removing means; and means located below said table top for operating said cutting and waste removing means.

16. A textile apparatus of the character described comprising; a device provided with power operable cutting means and a suction nozzle adjacent to the latter; means arranged to effect operation of the cutting means; a cutting waste receiver; suction generating means; conduit means connecting said suction nozzle, waste receiver and suction generating means; a work table provided with a substantially flat top section and means therebeneath for supporting the suction generating means, cutting waste receiver and means arranged to effect operation of the cutting means; and a bracket extending above said table top section arranged to maintain said device in a determined position.
